BOOKMARK AND LEAF CLAMP

Filed July 25, 1925

INVENTOR
M. J. KASIAN
BY *Wm. H. Leo*,
ATTORNEYS

UNITED STATES PATENT OFFICE.

MICHAEL JAMES KASIAN, OF CHICAGO, ILLINOIS.

BOOKMARK AND LEAF CLAMP.

Application filed July 25, 1925. Serial No. 46,151.

My invention relates to improvements in book marks and leaf clamps, and it consists in the combinations, constructions, and arrangements herein described and claimed.

5 An object of my invention is to provide a device of the character described which is intended to hold the pages of a book, magazine or pamphlet from turning over, while the book is open to a desired page.

10 A further object of my invention is to provide a device of the character described which without removal from engagement with the leaves of the book may be moved laterally across the page so as to permit the book to be closed, and which in this capacity serves as a book mark.

A further object of my invention is to provide a device of the character described which is constructed of yielding material so as not to damage the pages of the book or magazine, and which will conform with books of various thicknesses.

25 A further object of my invention is to provide a device of the character described which is simple in construction, that is durable and thoroughly practical for the purpose intended.

Other objects and advantages will appear in the following specification, and the novel 30 features of the invention will be particularly pointed out in the appended claims.

My invention is illustrated in the accompanying drawing forming part of this application, in which—

35 Figure 1 is a perspective view of an embodiment of my invention, and

Figure 2 is an elevation of the book with my book mark and leaf clamp applied thereto.

40 In carrying out my invention I make use of a body member 1, preferably constructed of relatively thick sheet celluloid. The body member 1 has a clip portion 2 at the upper end thereof, formed by bending the body at 3 so that the portion 2 will lie over the body 1.

The portion 2 is curved outwardly at its outermost end 4 so that the clip may be readily slipped over a plurality of pages, such 45 as shown at 5 of a book 6.

The clip portion 2 has a laterally extending leaf-engaging portion 7 which is approximately five inches in length, or sufficiently short to lie wholly upon one leaf of

the book 6, as shown in dotted lines in Figure 2, leaving sufficient space for the body member 1.

The leaf-engaging portion 7 is curved rearwardly, as viewed in Figure 1, so as to assure its engagement with the uppermost leaf 8 of the book 6 at the opposite side from the group of leaves 5 before mentioned.

The device is preferably manufactured from heavy sheet celluloid and is stamped 65 therefrom prior to bending the clip portion 2 back over the body member 1. This method of manufacture greatly simplifies and cheapens the cost of production.

From the foregoing description of the 70 various parts of the device the operation thereof may be readily understood. When the book 6 is closed, the device assumes the position shown in dotted lines in Figure 2, and permits the person having the book 75 to immediately open the pages so as to find the page 8, which is presumed to be, together with the opposite page, the pages sought for, when the device is used as a book marker.

When the pages are being read the entire device is shifted laterally to the position shown in full lines of Figure 2 so that the leaf-engaging portion 7 will contact and engage with the page 8. This construction will maintain the pages against movement 85 in either direction without the necessity of manually holding the book pages in the position desired, which is necessary at present when reading a book, particularly when there is a marked tendency of the pages to 90 close.

I claim:

1. A book mark and leaf clamp of the character described comprising a body member arranged for frictional engagement with certain of the leaves of a book or the like, and a single laterally extending leaf engaging portion formed integral with the body member and curved slightly intermediate its length toward the rear of the body member. 100

2. A book mark and leaf clamp of the character described comprising a body member arranged for frictional engagement with certain of the leaves of a book or the like, and a single laterally extending leaf engaging portion formed integral with the body member and curved slightly intermediate its length toward the rear of the body mem- 105

ber, said body member and leaf engaging portion being constructed of resilient material.

3. A book mark and leaf clamp of the character described comprising a body member arranged for frictional engagement with certain of the leaves of a book or the like, and a single laterally extending leaf engag-

ing portion formed integral with the body member and curved slightly intermediate its length toward the rear of the body member, said body member and said leaf engaging portion being constructed of transparent celluloid. 10

MICHAEL JAMES KASIAN.
